AMPLIFIER

Loy E. Barton, Collingswood, N. J., assignor to
Radio Corporation of America, a corporation of
Delaware

Original application January 30, 1932, Serial No.
589,846. Divided and this application May 29,
1933, Serial No. 673,370. In Spain January 24,
1933

15 Claims.

(Cl. 179—1)

My invention relates to amplifiers and, more particularly, to methods and apparatus for obtaining volume control in amplifiers of the type utilized in the reception of radio signals, and is a 5 division of my copending application, Serial No. 589,846, filed January 30, 1932 for Amplifiers, and assigned to the same assignee.

Many automatic volume control systems, as heretofore devised, have been open to some objection because of the necessity for providing an additional thermionic tube to supply grid biasing potentials varying in response to fluctuations in carrier amplitude. Furthermore, by reason of the fact that volume control systems, in 15 general, permit maximum amplifier sensitivity when no carrier is being received, the background noise received when tuning from one station to another has been excessive and unpleasant.

20 In addition, automatic volume control systems that respond to modulation are open to the objection that static, if strong, causes temporary paralysis of reception while the bias potential resulting from the static is being dissipated. Attempts at rendering the systems unresponsive to static involve the use of circuits having time-constants within the audio range. If circuits having time-constants too short are used, low 25 audio frequencies are effected, if too long, the recovery from a static discharge is slow.

The invention further contemplates the use of 30 manual volume control means in the said amplifying system, and with the automatic volume control means preceding said manual volume control means, whereby signal potentials of substantially constant average amplitude are supplied to the manual volume control means.

It is, accordingly, an object of my invention 35 to provide an improved volume control system that shall not be open to the foregoing enumerated objections.

It is a further object of my invention to provide an improved tone compensated volume control system for use in connection with audio 40 frequency circuits, which is simple and effective, and involves comparatively inexpensive circuit elements.

45 Preferably, in practising my invention, I consolidate the functions of demodulation of a signal and the supplying of a volume control potential into a single thermionic device, thus eliminating the customary extra volume-control tube.

The circuit is so arranged that the automatic 50 volume control does not reduce the volume in a linear relation to the input signal, but gives little control until a predetermined signal amplitude is received, after which any further increase results in rapid automatic volume control.

55 I also provide means whereby the automatic control so responds to the carrier wave only that

static discharges have relatively little effect on volume or sensitivity.

Since automatic volume control responds primarily to carrier, low frequency modulation or peak modulation does not affect the automatic 5 volume control.

The manual volume control means is located in an audio frequency circuit, such as the detector output circuit, and is provided with tone compensating means including a tapped potentiometer device shunted in part by audio frequency signal attenuating circuits connected to suitably spaced taps thereon, to gradually effect a desired tone control for predetermined volume levels, simultaneously with the adjustment of the 15 volume. This may be designated as an automatically tone compensated volume control system.

The novel features that I consider characteristic of my invention are set forth with particularity in the appended claims. The invention itself, however, both as to its organization and its method of operation, together with additional objects and advantages thereof, will best be understood from the following description of a 25 specific embodiment, when read in connection with the accompanying drawing, in which the single figure is a diagrammatic view of a portion of an amplifier provided with volume control means according to my invention. 30

In common with other automatic volume control systems I provide biasing means, for one or more amplifying tubes, responsive to the amplitude of an incoming carrier-wave. In my improved system, referring to the drawing, the 35 biasing means includes a thermionic tube 1, having a cathode 3, a plurality of grids 5, 7, and 9, and an anode 11. The screen grid pentode tube commercially designated RCA-238, is satisfactory. 40

One of the grids, preferably the grid 5, commonly used as a screen grid, is connected through a resistor 13 to a source 15 of positive potential. The grid 9, which serves as the input or control electrode, is connected to the cathode through 45 an inductor 17, which may or may not be provided with a tuning condenser 19, and a fixed condenser 21.

Normal bias for the thermionic device 1, sufficiently negative to enable it to function satisfactorily as a demodulator, is provided by connecting the control-grid 9 through a resistor 23, to the junction 24 between the negative terminal of the high potential anode-supply source and a resistor 25 interposed between the said terminal 55 and the cathode of the device.

The potential dividers 25 and 26 across the voltage supply furnish the necessary potential to keep the grid negative with respect to the cathode.

The anode 11 of the thermionic device 1 is con- 60

nected, through a tuned circuit 27 and a resistor 29 and the resistor 25, back to the cathode, the connection being devoid of a positive potential source.

5 Input potentials for the demodulating device 1 may be supplied at radio frequency or at intermediate frequency depending upon the point of application, in an amplifier, of my improved volume control system. For purposes of illustration, I have indicated that such input potentials are at an intermediate frequency and are derived from the output circuit of an intermediate frequency amplifier tube 31 of the four-electrode type, having a cathode 33, a plurality of grids 35 and 37, and an anode 39.

10 The grid 35 of the intermediate frequency amplifier tube is connected to the cathode thereof through an inductor 41, which may or may not be provided with a tuning condenser 43, but includes a by-pass condenser 45. The cathode 33 of the device is connected to the junction point 24 between the cathode of the demodulator tube 1 and the aforementioned resistor 25, through a self-bias resistor 47.

15 The grid 35 of the intermediate frequency amplifier tube is connected to the junction point 24 through a resistor 48 and the resistor 29 included in the anode circuit of the demodulator tube. Normal negative grid bias potential for the intermediate frequency amplifier tube, therefore, is supplied by the drop across the self-bias resistor 47, the magnitude of the resistor being so chosen with respect to the plate and screen grid potentials supplied that the said drop is correct for 20 maintaining the proper normal bias.

25 In the operation of my improved system, signals impressed upon the demodulator tube from the previous amplifying stage are demodulated therein and appear as signals at audio frequency in the output circuit including the screen grid 5 and the resistor 13. Since, as is well known to those skilled in the art, the output current from the demodulator tube includes a component at the carrier frequency, the said component will be re-impressed between the anode and the cathode of the tube, by reason of the inductive coupling existing between the output inductor 27 and an inductor 49 connected in shunt relation to the resistor 13 insofar as the carrier frequency is concerned. A small condenser 50, offering high impedance to audio frequency, is included in circuit with the inductor 49. The low impedance of the circuit 49-50 to carrier, and high impedance to audio frequency result in relatively 30 low percentage modulation of the carrier frequency induced in the inductor 27. This has an important practical result, i. e., only small amounts of static frequencies are re-impressed on the detector 1. The carrier, thereafter, is again 35 rectified in the demodulator tube, giving rise to a uni-directional current which flows between the anode and the cathode of the device in the circuit including the output inductor 27, the resistor 29, and the resistor 25.

40 Because of the high impedance of the resistor 13 to audio frequencies, the energy or signal transferred to circuit 27 has only a limited degree of modulation as compared to the original carrier. This feature results in an automatic 45 volume control that is more or less independent upon frequency of modulation down to perhaps ten cycles and does not respond appreciably to static. The direction of current flow in the resistor 29 is such that the end thereof connected 50 to the grid of the intermediate frequency ampli-

5 fier tube acquires a negative potential with respect to the end which is connected to the cathode and, as a consequence, the bias potential applied to the said intermediate frequency amplifier becomes more negative than normal, the increase 5 in the negative direction being proportional to the amplitude of the carrier wave impressed upon the demodulator tube.

10 It should be noted that the anode 11, of the tube 1, is at all times, maintained somewhat negative with respect to the cathode thereof by reason of the drop across the resistor 25. This is a desirable feature since it prevents the automatic volume-control from functioning until a signal of predetermined volume is reached.

15 The self-bias rheostat 47 controls the maximum sensitivity and it may, with advantage, be manipulated during tuning to minimize background noise between stations. Preferably the resistance of the rheostat is high, of the order of 20 3000 ohms which may be adjusted to a predetermined minimum value for maximum sensitivity.

20 As hereinbefore explained, my improved automatic volume control so functions that the gain in the amplifier, for all signals above a certain 25 predetermined minimum value, is inversely proportional to carrier amplitude. Such being the case, further means are required for controlling the sound output, from a loudspeaker (not shown) to meet different requirements.

25 It is also desirable that, at low sound intensities, the high frequencies shall be somewhat more attenuated than the low frequencies.

30 I, accordingly, interpose a coupling network, for obtaining automatically compensated volume 35 control, between the resistor 13 included in the output circuit of the detector tube 1 and the input terminals of an audio-frequency amplifying tube 51. The audio frequency amplifying tube may be of the equipotential cathode type having 40 an anode 52, a grid 53, and a cathode 55. A self-bias resistor 57 shunted by a condenser 59, is interposed between the cathode 55 and ground and the grid 53 is connected to ground through a condenser 61 for additional manual tone-control 45 purposes hereinafter to be explained more in detail.

45 The coupling network includes the resistance element 63 of a potentiometer, one end of which is connected to the grid 5 of the detector tube 50 through a stopping condenser 65 and a resistor 67 and the other end of which is connected to ground through a grid-leak 69. The resistor 67 and a by-pass condenser 70 serve to effectively attenuate the carrier frequency and prevent it 55 from appearing on the grid of the tube 51. Since the resistor 67 offers high impedance to the carrier frequency, it is compelled to take a path to ground including the inductor 49 which offers 60 low impedance to the carrier frequency. The junction between the resistance element of the potentiometer and the grid leak is connected to the cathode through a condenser 71 which acts as a hum filter.

65 In order that the potentials, at high frequencies, developed across the potentiometer resistance element 63, shall be progressively attenuated as the movable arm thereof is moved down, in the direction giving reduced volume, separated 70 points on the element are by-passed to the cathode over paths including individual condensers 75 and 77, individual resistors 79 and 81, and the condenser 71, previously mentioned.

75 It should be clear, from a consideration of the foregoing, that the low frequency potentials im-

pressed on the amplifying tube 51, since the potentiometer is not appreciably bypassed for them, are attenuated less than the high frequencies, thus giving the desired effect. The degree of compensation depends upon the resistance between taps on the resistor 63 in relation to the condensers 75 and 77 and the resistors 79 and 81. If further attenuation of the high frequencies is wished for, independently of the position of the potentiometer arm 73, a resistor 83, interposed between the arm and the grid of the tube 51 may be varied to control the shunting action of the condenser 61 connected between the grid and the cathode. A very small condenser 84 may be interposed between the resistor 63 and the arm 73, if extremely high frequencies are to be compensated to some extent.

By way of example, the resistor or impedance element 63 may have a resistance of 500,000 ohms and may be, and preferably is, wholly constituted by the resistance element of a potentiometer device. The condensers 75 and 77 may have values of .0025 and .025 microfarad, respectively, while the resistors 79 and 81 may have values of 100,000 ohms and 10,000 ohms, respectively.

In order that the disclosure of my improved automatic volume control system shall be complete, I am giving below a list of other more important circuit constants:

Resistor	Ohms	Condenser	Microfarads
13	50,000 to 100,000	50	.000750
29	50,000 to 200,000	61	0-.0001
35	20,000	65	.1
67	0-1 megohm	70	.0002
83		84	.0001

Although I have chosen a specific embodiment of my invention for purposes of illustration, many modifications thereof will be apparent to those skilled in the art to which it pertains. For example, for a different degree of compensation, different values of certain of the circuit components as above given may be changed. Particular reference is had to the circuit components 75 and 77 together with the limiting resistors 79 and 81, and the spacing between the tap connections therefor with the volume control resistor 63.

My invention, therefore, is not to be restricted except insofar as is necessitated by the prior art and by the spirit of the appended claims.

I claim as my invention:

1. In an audio frequency volume control circuit to which signals of substantially constant average amplitude are applied, a volume and tone control network including a continuously variable volume control potentiometer resistor having terminal ends, a plurality of fixed spaced taps thereon between and spaced from said ends, means including electrical impedance elements providing separate shunt connections between each of said taps and one end of said resistor, and means providing at least one variable output tap connection movable along said resistor between said ends and successively past said first named taps.

2. In an audio frequency volume control circuit to which signals of substantially constant average amplitude are applied, a single variable volume control means comprising an impedance element having terminal ends connected with said circuit and spaced taps between said ends, and means in circuit separately between one terminal and each of said taps for attenuating

signals within certain portions of the audio frequency range, said means thereby being effective with variations in volume, and being connected in shunt relation to portions of said impedance element through said taps and said one terminal.

3. In an audio frequency signal transmission circuit, means for supplying audio frequency signals thereto at substantially constant average amplitude, a potentiometer device having an impedance element connected in shunt with said circuit, an output circuit connected with one terminal and the variable contact of said potentiometer device and a plurality of signal attenuating circuits connected each with said one terminal and a separate fixed tap point intermediate the ends of said impedance element, said tap points being spaced apart along said impedance element progressively to provide attenuation progressively with decrease in volume by adjustment of said contact.

4. In an audio frequency signal transmission circuit, a potentiometer device having an impedance element connected in shunt with said circuit, an output circuit connected with one terminal and the variable contact of said potentiometer device and a plurality of signal attenuating circuits connected each with said one terminal and a separate fixed tap point on said impedance element, said tap points being spaced apart progressively along said impedance element to progressively attenuate signals with decrease in volume by adjustment of said contact, and at least one of said circuits including a condenser and a resistor connected in series, thereby to attenuate signals in the higher audio frequency range.

5. In an audio frequency signal transmission circuit, a potentiometer device having an impedance element connected in shunt with said circuit, an output circuit connected with one terminal and the variable contact of said potentiometer device, and a plurality of separate signal attenuating circuits connected each between said one terminal and a separate fixed tap point intermediate the ends of said impedance element, said tap points being spaced apart progressively along said impedance element and each of said signal attenuating circuits having a lower impedance to a certain range of audio frequency signals than the impedance of that portion of the potentiometer device with which it is effectively connected in parallel.

6. In combination, a potentiometer device comprising an electrical impedance element and a contact movable along said impedance element to provide a variable connection therewith, said impedance element having a series of taps spaced progressively between its terminal ends, a plurality of separate signal attenuating frequency responsive means each connected with one of said terminal ends and with a separate one of said taps, automatic volume control means for supplying audio frequency signals of substantially constant amplitude to the terminals of said impedance element, and an output circuit connected to said movable contact and one terminal end of said element, whereby movement of said contact toward said terminal end provides volume reduction and progressive signal attenuation.

7. In combination, a potentiometer device comprising an electrical impedance element and a contact movable along said impedance element to provide a variable connection therewith, said impedance element having taps spaced progressively between its terminal ends, a plurality of

separate signal attenuating means each connected with one of said terminal ends and with a separate one of said taps, thereby progressively to attenuate signals as the contact is moved in the 5 direction of said one terminal end, an audio frequency signal circuit connected with the terminal ends of said impedance element, and an audio frequency output circuit connected with said one of the terminal ends of said impedance element 10 and the movable contact.

8. In combination, a potentiometer device comprising an electrical impedance element and a contact movable along said impedance element to provide a variable connection therewith, said 15 impedance element having spaced taps between its terminal ends, a plurality of signal attenuating means each connected with one of said terminal ends and with a separate one of said taps, an audio frequency signal circuit connected with 20 the terminal ends of said impedance element, an audio frequency output circuit connected with said one of said terminal ends of said impedance element and the movable contact, and independent additional tone control means connected 25 in said output circuit between said contact and a high potential end of said impedance element.

9. In combination, a potentiometer device comprising an electrical impedance element and a contact movable along said impedance element to provide a variable connection therewith, said 30 impedance element having spaced taps between its ends, a plurality of signal attenuating means each connected with one of said ends and with a separate one of said taps, an audio frequency signal circuit connected with the terminal ends 35 of said impedance element, an audio frequency output circuit connected with said one of said terminal ends of said impedance element and the 40 movable contact, and a high frequency filter in said audio frequency input circuit comprising a shunt coupling impedance, a series impedance in one side of said circuit, and a condenser connected in parallel with said circuit following said 45 impedance in the direction of signal transmission.

10. In an audio frequency amplifier system, an audio frequency amplifier device having an output circuit, a second audio frequency amplifier device having an input circuit, and a volume control coupling network interconnecting said circuits for progressively attenuating signals in certain portions of the audio frequency range with decrease in volume, said network comprising a 50 potentiometer resistor having a resistance element connected in shunt to said output circuit, a movable contact and one terminal connected with said input circuit, and a plurality of signal attenuating means connected to provide separate circuits between said one terminal and spaced 55 tap points between and spaced from the terminals of said resistance element.

11. In an audio frequency amplifier system, an audio frequency amplifier device having an output circuit, a second audio frequency amplifier device having an input circuit, and a coupling network providing combined volume and tone control, interconnecting said circuits and comprising a potentiometer resistor having a resistance element connected in shunt to said output circuit, and a plurality of signal attenuating 65

means connected between said one terminal and spaced tap points arranged in spaced relation to each other progressively along said resistor, said signal attenuating means each comprising a condenser and a resistor connected in series with each other for providing differing decrease of signal attenuation progressively as said contact is moved toward said one terminal. 5

12. In an audio frequency amplifier system, an audio frequency amplifier device having an output circuit, a second audio frequency amplifier device having an input circuit and a coupling network interconnecting said circuits and comprising a potentiometer resistor having a resistance element connected in shunt to said output 10 circuit, a movable contact and one terminal connected with said input circuit, and a plurality of signal attenuating means connected between said one terminal and spaced tap points thereon, and a separate variable tone control 15 means connected with said input circuit. 20

13. In an audio frequency amplifier system, an audio frequency amplifier device having an output circuit, a second audio frequency amplifier device having an input circuit and a coupling network interconnecting said circuits and comprising a potentiometer resistor having a resistance element connected in shunt to said output circuit, and a plurality of signal attenuating means connected between said one terminal and spaced 25 tap points on said resistance element, said signal attenuating means each comprising a condenser and a resistor connected in series with each other, and a separate compensating circuit connection between the output circuit and the input circuit, 30 said connection including a coupling condenser of relatively low capacity. 35

14. In an audio frequency volume control circuit, a volume control potentiometer device having a resistance element provided with high potential and low potential input terminals at its ends, a tap continuously movable along said element between said ends, a signal output circuit connected with said movable tap and the low potential terminal, a signal input circuit connected 40 with said high and low potential terminals, said element having a series of taps spaced from said high potential terminal and from each other, and a separate tone compensating circuit including a reactance element connected between each of said 45 last named taps and the low potential terminal of said first named element. 50

15. In an audio frequency signal transmission circuit, a potentiometer device having an impedance element connected in shunt with said circuit, an output circuit connected with one terminal and the variable contact of said potentiometer device, and a plurality of signal attenuating circuits connected each with said one terminal and a separate fixed tap point on said 55 impedance element, said tap points being spaced apart progressively along said impedance element to progressively attenuate signals with decrease in volume by adjustment of said contact, and at least one of said circuits including a 60 condenser and a resistor connected in series, said circuit being connected with a tap point whereby it becomes effective in advance of said other circuits in the attenuation of said signals. 65
